UNITED STATES PATENT OFFICE.

ALEX SHOLUND, OF MARYSVILLE, WASHINGTON.

FENCE-POST.

1,280,093.

Specification of Letters Patent. Patented Sept. 24, 1918.

Application filed May 14, 1918. Serial No. 234,446.

To all whom it may concern:

Be it known that I, ALEX SHOLUND, a citizen of the United States, residing at Marysville, in the county of Snohomish and State of Washington, have invented new and useful Improvements in Fence-Posts, of which the following is a specification.

This invention relates to fence posts and it consists in the novel features hereinafter 10 described and claimed.

An object of the invention is to provide a metal post of simple and durable structure adapted to be driven in the ground and having a base flange adapted to limit the extent 15 to which it is forced into the ground. One end of the body of the post is pointed and adapted to enter the ground and the opposite end thereof is closed whereby the body which is hollow may be readily driven or 20 forced into the ground.

The body is provided at intervals along its length with outstanding ears 5 under which recesses are provided the said recesses being adapted to receive line wires. The 25 body is further provided above the said recesses with lugs and a ring or a series of rings may be applied to the body. Each ring is provided at its inner side with a transversely disposed groove adapted to pass 30 over the lugs and ears when the ring is slipped from the upper to the lower portion of the post. Each ring is provided at its interior surface with a spiral groove one end of which communicates with the said trans- 35 versely disposed groove and the other end is closed. The said spiral groove is adapted to receive the lug 6 when the ring is turned whereby the lower edge of the ring may be forced into the ground into close contact 40 with the upper end of the adjacent ear and consequently the wire which is in the recess under the ear is securely retained therein.

In the accompanying drawing:—

Figure 1 is a side elevation of the fence 45 post.

Fig. 2 is a fragmentary side elevation of the same with parts in section.

Fig. 3 is a plan view of a ring used upon the post.

50 Fig. 4 is a sectional view of the ring cut on the line 4—4 of Fig. 3.

The post comprises an elongated body 1 which is hollow and closed and pointed at one end as at 2 and closed at its upper end as at 3. The said body 1 is provided at a 55 point between its end with an outstanding annular flange 4 adapted to come in contact with the surface of the ground when the pointed end of the body is driven therein.

The said body is further provided at intervals along its length with outstanding ears 5 under each of which there is provided a transversely disposed recess 7. Lugs 6 are located at one side of the body 1 above the recesses 7 and are spaced from the upper 65 ends of the ears 5.

Each body 1 is adapted to be provided with a series of rings 8 and the said rings may slide along the body. Each ring is provided at its interior with a transversely 70 disposed groove 9 and the said groove may slip over the ears and lugs 6 when the ring is being passed from an upper portion of the body to a lower portion thereof. Each ring 8 is further provided at its interior surface with a spiral groove 10 one end of which communicates with one end portion of the groove 9 and the opposite end of the groove 10 is closed as at 11 and terminates short of 75 the side of the groove 9.

When the post is driven in position in the ground the line wires of a fence fabric may be placed in the recesses 7. Consequently the fence fabric is supported by the post. Then each ring 8 is moved down so that the 80 adjacent lug 6 is received in the lower portion of the groove 9. The ring 8 is then turned whereby the lug 6 moves along the groove 10 and inasmuch as the said groove 10 is spirally disposed the ring will be forced 85 down in close contact with the upper end of the adjacent ear 5 and consequently the line wire is securely retained in place in the adjacent recess 7. To release the wire and remove the rings and fence fabric from the 90 post the operation above described is reversed.

From the foregoing description taken in conjunction with the accompanying drawing it will be seen that a substantial fence post 100 of simple and durable structure is provided and that the same is provided with means

for effectually retaining the line wires of a fence fabric in position thereon.

Having described the invention what is claimed is:—

- 5 A fence post, a body, an ear provided thereon and having a recess located under the same, a lug located above the recess and

car, a ring slidably mounted on the body and having a transversely disposed groove adapted to pass over the ear and lug and 10 provided with a spiral groove adapted to receive the lug when the ring is turned.

In testimony whereof I affix my signature.

ALEX SHOLUND.
